COMBINED HOLDER AND COASTER FOR CANNED BEVERAGES

Robert H. Relly, Springfield Township, Hamilton County, and Robert V. Tynan, Colerain Township, Hamilton County, Ohio

Application July 29, 1955, Serial No. 37,217

Term of patent 3½ years

(Cl. D44—10)

Fig. 1.

Fig. 2.

Figure 1 is a view in side elevation of the combined holder and coaster for canned beverages, showing our new design, a beverage can being shown in dot-dash lines in relation thereto; and

Fig. 2 is a view in perspective thereof.

The dominant feature of the design resides in the full line portion of the drawing.

We claim:

The ornamental design for a combined holder and coaster for canned beverages, as shown and described.
